- [57] ABSTRACT
- An organophosphate ester having the formula

substituted

wherein

A represents a divalent radical selected from the group consisting of alkylene having three to five carbon atoms, aza substituted alkylene having three to five carbon atoms in the chain and thia substituted alkylene having three to five carbon atoms in the chain,

Y' represents a member selected from the group consisting of hydrogen, alkyl having one to six carbon atoms, cyano, halo and alkylthio having one to six carbon atoms,

X represents a member selected from the group consisting of sulfur and oxygen,

R1'' represents an alkyl having one to four carbon atoms,

R2'' represents a member selected from the group consisting of alkyl having one to four carbon atoms, alkoxy having one to four carbon atoms, alkoxyalkoxy having one to four carbon atoms in each alk, and

where R1' and R2' are members selected from the group consisting of hydrogen and alkyl having one to three carbon atoms; as well as the process of producing said organophosphate esters. The compounds have insecticidal and acaricidal properties.

4 Claims, No Drawings

ORGANOPHOSPHATE ESTER DERIVATIVES OF HETEROCYCLIC COMPOUNDS AND PROCESS

OBJECTS OF THE INVENTION

An object of the present invention is obtaining an organophosphate ester having the formula

wherein

A represents a divalent radical selected from the group consisting of alkylene having three to five carbon atoms, aza substituted alkylene having three to five carbon atoms in the chain and thia substituted alkylene having three to five carbon atoms in the chain,

Y' represents a member selected from the group consisting of hydrogen, alkyl having one to six carbon atoms, cyano, halo and alkylthio having one to six carbon atoms,

X represents a member selected from the group consisting of sulfur and oxygen,

R₁'' represents an alkyl having one to four carbon atoms,

R₂'' represents a member selected from the group consisting of alkyl having one to four carbon atoms, alkoxy having one to four carbon atoms, alkoxyalkoxy having 1 to 4 carbon atoms in each alkyl, and

where R₁' and R₂' are members selected from the group consisting of hydrogen and alkyl having one to three carbon atoms.

Another object of the present invention is the development of a process for the production of the above organophosphate esters which consists essentially of reacting a heterocyclic compound having the formula

wherein A represents a divalent radical selected from the group consisting of alkylene having three to five carbon atoms, aza substituted alkylene having three to five carbon atoms in the chain and thia substituted alkylene having three to five carbon atoms in the chain and Y' represents a member selected from the group consisting of hydrogen, alkyl having one to six carbon atoms, cyano, halo and alkylthio having one to six carbon atoms, with a halophosphate having the formula

wherein Hal represents a member selected from the group consisting of chloro and bromo, X represents a member selected from the group consisting of sulfur and oxygen, R₁'' represents an alkyl having one to four carbon atoms and R₂'' represents a member selected from the group consisting of alkyl having one to four carbon atoms, alkoxy having one to four carbon atoms, alkoxyalkoxy having one to four carbon atoms in each alkyl, and

where R₁' and R₂' are members selected from the group consisting of hydrogen and alkyl having one to three carbon atoms, and recovering said organophosphate ester.

A further object of the present invention is the development of insecticidal and/or acaricidal compositions containing from 10 percent to 80 percent of the above organophosphate esters and the remainder inert excipients.

A yet further object of the present invention is the development of a method for combatting insects and/or acarids which comprises contacting them with the above organophosphate esters.

These and other objects of the invention will become more apparent as the description thereof proceeds.

DESCRIPTION OF THE INVENTION

The above objects have been achieved by the discovery of novel insecticidal and/or acaricidal organophosphate ester derivatives of the general formula I

(I)

in which

A represents an alkylene chain having from three to five carbon atoms, possibly interrupted by a heteroatom chosen from sulfur and nitrogen, and more particularly A represents a divalent radical selected from the group consisting of alkylene having three to five carbon atoms, aza substituted alkylene having three to five carbon atoms in the chain and thia substituted alkylene having three to five carbon atoms in the chain;

Y' represents hydrogen, alkyl having one to six carbon atoms, linear or branched, cyano, halo and alkylthio having one to six carbon atoms, and more particularly Y' represents a member selected from the group consisting of hydrogen, alkyl having

one to six carbon atoms, cyano, halo and alkylthio having from one to six carbon atoms; X represents an atom of sulfur or oxygen; R₁'' represents an alkyl, linear or branched, having one to four carbon atoms; and R₂'' represents an alkyl, linear or branched, having one to four carbon atoms, alkoxy having one to four carbon atoms and possibly substituted by alkoxy having one to four carbon atoms, or R₂'' represents an amino group

in which R₁' and R₂', the same or different, represent either hydrogen or an alkyl, linear or branched, having one to three carbon atoms, and more particularly R₂'' represents a member selected from the group consisting of alkyl having one to four carbon atoms, alkoxy having one to four carbon atoms, alkoxyalkoxy having one to four carbon atoms in each alk, and

where R₁' and R₂' are members selected from the group consisting of hydrogen and alkyl having one to three carbon atoms.

The term "alkyl" used here above designates particularly methyl, ethyl, propyl, isopropyl or n-butyl and the term "alkoxy," methoxy, ethoxy, propoxy, isopropoxy or n-butoxy.

Among the compounds of formula I, those of particular interest are the following:

- a. 2-diethoxythiophosphoryloxy-3-bromo-7,8-dihydro-6H-pyrrolo-[1,2-a]-pyrimidine-4-one;
- b. 2,3-dihydro-8-diethoxythiophosphoryloxy-4H-pyrimido-[2,1-b]-[1,3]-thiazine-6-one;
- c. 2,3-dihydro-7-dimethoxythiophosphoryloxythiazola-[3,2-a]-pyrimidine-5-one;
- d. 1,6-dihydro-4-diethoxyphosphoryloxyazepino-[1,2-a]-pyrimidine-6-one;
- e. 2-(methoxy-ethoxy-thiophosphoryloxy)-7,8-dihydro-6H-pyrrolo-[1,2-a]-pyrimidine-4-one;
- f. 2-dipropoxythiophosphoryloxy-7,8-dihydro-6H-pyrrolo-[1,2-a]-pyrimidine-4-one;
- g. 2-diisopropoxythiophosphoryloxy-7,8-dihydro-6H-pyrrolo-[1,2-a]-pyrimidine-4-one;
- h. 2-diethoxythiophosphoryloxy-3-ethylthio-7,8-dihydro-6H-pyrrolo[1,2-a]-pyrimidine-4-one.

The compounds of formula I are endowed with pesticidal properties particularly as insecticides and/or acaricides which make them suitable to control noxious organisms and particularly insects and acarids.

The insecticidal properties of these compounds can be demonstrated particularly by tests on *Prodenia litura*, *Ceratitis capitata*, *Aphis fabae*, *Blatella germanica* or *Musca domestica* which are described later.

The process of preparation of the organophosphate ester derivatives of formula I is characterized in that a compound of the formula II:

5

(II)

wherein A and Y' have the above-assigned values, is reacted with a halogenophosphate of the formula III:

10

(III)

15

in which Hal represents chlorine or bromine and X, R₁'' and R₂'' have the above-assigned values.

In a preferred method, a chlorophosphate is utilized as the halogenophosphate of formula III. The condensation reaction may be conducted in an organic solvent such as acetone, acetonitrile, benzene, methanol or ethyl acetate, under, preferably, anhydrous conditions in the presence of a basic agent such as an alkali metal carbonate, an alkali metal lower alkanolate and/or a tertiary organic amine base such as triethylamine, trimethylamine or pyridine. The basic agent may also be the alkali metal derivative of the compound of formula II as formed from the reaction of the compound of formula II with an alkali metal lower alkanolate in a solvent such as a lower alkanol.

In the case where Y' is hydrogen, R₁'' represents an alkyl and R₂'' represents an alkoxy, for compounds of formula I, these compounds can be prepared by reacting a compound of the formula

40

with a trialkyl phosphite. Preferably, this reaction is conducted with an excess of the trialkyl phosphite and for example at temperatures of from 50°C to 125°C.

The invention also comprises the insecticidal and/or acaricidal compositions containing, as active material, at least one of the compounds of formula I. These compositions can be presented in the form of powders, granules, suspensions, emulsions, solutions, containing the active principle, for example, in mixture with a vehicle and/or an anionic, cationic or nonionic surface-active agent assuring, among other things, a uniform dispersion of the substances of the composition. The vehicle utilized can be a liquid such as water, alcohol, hydrocarbons or other organic solvents, mineral, vegetable or animal oil, or a powder such as talc, clays, silicates, Kieselguhr.

The insecticidal liquids or powders for foliage applications contain preferably from 20 to 80 percent by weight of the active material Formula I.

The acaricidal liquids or powders for foliage applications contain preferably from 20 percent to 80 percent by weight of the active material of formula I.

45

50

55

60

65

An emulsifiable concentrate can be prepared as an insecticidal composition containing, for example, by weight 15 percent of 2-dimethoxythiophosphoryloxy-7,8-dihydro-6H-pyrrolo-[1,2a]-pyrimidine-4-one pyrrolo-4-pyrimidone, 6.4 percent of "Atlox" 4851 (oxy-ethylenated triglyceride combined with a sulfonate, acid number: 1.5), 3.2 percent of Atlox 4855 (oxyethylenated triglyceride combined with a sulfonate, acid number: 3) and 75.4 percent of xylene.

The invention also comprises a process of combatting insects and/or acarids characterized in that a composition containing as active material at least one of the compounds of formula I and possibly in addition, one or several other pesticidal agents is contacted with the insects and/or acarids.

The compounds of formula II, utilized as starting materials in the process of the invention, can be prepared according to a process analogous to that described by Le Berre et al, Bull. Soc. Chim. 1969, 3137.

4-hydroxy-1,6-dihydro-azepino-[1,2-a]-pyrimidine-6-one was described by Glushkov et al, Zhur. Obshchei, Khim. 31, 189 (1961). 2,3-dihydro-7-hydroxy-thiazolo-[3,2-a]-pyrimidine-5-one was described by Dashkevich, Zhur. Obshchei, Khim. 31, 3723 (1961).

Certain compounds of formula II are not described in the literature. These are 2-hydroxy-6,7,8,9-tetrahydro-pyrido-[1,2-a]-pyrimidine-4-one, 2-hydroxy-3-ethylthio-7,8-dihydro-6H-pyrrolo-[1,2-a]-pyrimidine-4-one, 1,6-dihydro-4-hydroxy-5-bromo-azepino-[1,2-a]-pyrimidine-6-one, and 1,6-dihydro-4-hydroxy-5-isopropyl-azepino-[1,2-a]-pyrimidine-6-one, all of whose preparations are given as exemplary later in the examples.

The compounds of the formula

can be prepared by the action of N-bromo-succinimide on compounds of the formula

The following examples are illustrative of the practice of the invention without being deemed limitative in any respect.

EXAMPLES

Preparation A:

2-hydroxy-6,7,8,9-tetrahydro-pyrido-[1,2a]-pyrimidine-6-one

6.5 gm of sodium were introduced into 300 cc of ethanol and, after the disappearance of the sodium, 19 gm of imino-pyridine hydrochloride and 22.5 gm of ethyl malonate were added thereto. The reaction mixture was heated to reflux and maintained there for sixteen hours. The insolubles formed were eliminated by filtra-

tion. The reaction mixture was concentrated to dryness and some water was added thereto. The aqueous mixture was acidified to a pH of 3 by the addition of an aqueous solution of hydrochloric acid. The precipitate formed was isolated by vacuum filtering and 13.8 gm of 2-hydroxy-6,7,8,9-tetrahydro-pyrido-[1,2-a]-pyrimidine-4-one melting at 270°C (with decomposition), was obtained.

I.R. Spectra

absorption at 1709 and 1606 cm^{-1} corresponding to C=O,
absorption at 1587 cm^{-1} corresponding to C=C,
absorption at 1529 cm^{-1} corresponding to C=N.

15

Preparation B

2-hydroxy-3-ethylthio-7,8-dihydro-6H-pyrrolo-[1,2-a]-pyrimidine-4-one

20

19.5 gm of imino-pyrrolidine and 52 gm of ethyl ethylthio-malonate were mixed. This mixture was heated to 200°C, maintained at this temperature for fifteen minutes, and then cooled. The residue obtained was ground in the presence of ether. The resulting powder was isolated by vacuum filtering and 31 gm of 2-hydroxy-3-ethylthio-7,8-dihydro-6H-pyrrolo-[1,2-a]-pyrimidine-4-one was obtained.

I.R. Spectra

absorption at 1720 cm^{-1} corresponding to C=O,
absorptions corresponding to C=C, C=N, OH.

30

Preparation C:

azepino-[1,2-a]-pyrimidine-6-one
4-hydroxy-5-bromo-1,6-dihydro-

35

37 gm of 4-hydroxy-1,6-dihydro-azepino-[1,2-a]-pyrimidine-6-one was introduced into 300 cc of methanol. 36.6 gm of N-bromo-succinimide were added progressively and then the reaction mixture was agitated for 16 hours at room temperature. The precipitate formed was isolated by vacuum filtering, washed and dried. 38 gm of 4-hydroxy-azepino-[1,2-a]-pyrimidine-6-one 5-bromo-1,6-dihydro, melting at 265°C (with decomposition), was obtained.

I.R. Spectra

absorption at 1694 cm^{-1} , 1683 cm^{-1} , corresponding to C=O,
absorption at 1618 cm^{-1} , corresponding to C=C,
absorption at 1569 cm^{-1} and 1540 cm^{-1} , corresponding to C=N,
absorption corresponding to OH.

40

Preparation D:

1,6-dihydro-4-hydroxy-5-isopropyl-azepino-[1,2-a]-pyrimidine-6-one

45

45 gm of sodium ethylate were introduced into 450 cc of ethanol. 63 gm of ethyl isopropyl-malonate and 50 gm of the sulfate of caprolactamidine were added to the solution obtained. The reaction mixture was heated to reflux and maintained there for four hours. The solvent was then eliminated by distillation under reduced pressure. The residue was dissolved in water and acidified to a pH of 3 with an aqueous hydrochloric acid solution. The precipitate formed was isolated by vacuum filtration and dried. 47 gm of 1,6-dihydro-4-hydroxy-5-isopropyl-azepino-[1,2-a]-pyrimidine-6-one was obtained, which was purified by dissolution in an aqueous sodium hydroxide solution, this solution being washed

55

60

65

with ethyl acetate and acidified to a pH of 4. The purified product had a melting point of 246°C.

EXAMPLE 1

2-Diethoxythiophosphoryloxy-7,8-dihydro-6H-pyrrolo-[1,2-a]-pyrimidine-4-one

36 gm of 2-hydroxy-7,8-dihydro-6H-pyrrolo-[1,2-a]-pyrimidine-4-one were placed in suspension in 300 cc of acetone. After homogenization, 28 cc of triethylamine were added, then 35 cc of O,O-diethyl chlorothiophosphate were introduced drop by drop. The mixture was agitated at room temperature for forty-eight hours. Then the precipitate was eliminated by filtration and the filtrate was evaporated to dryness under reduced pressure. A raw oil was obtained which was subjected to chromatography through a column of silica eluting with a chloroform-acetone mixture (1:1). The Rf 0.5 fraction was evaporated to dryness under reduced pressure. A yellow oil was obtained which crystallized giving 28 gm of yellow crystals of 2-diethoxythiophosphoryloxy-7,8-dihydro-6H-pyrrolo-[1,2-a]-pyrimidine-4-one melting at 56°C.

Analysis:

$C_{11}H_{17}N_2O_4PS$; molecular weight = 304.307

Calculated:

EXAMPLE 2

2-(N-methyl-O-ethyl-thiophosphoramido-oxy)-7,8-dihydro-6H-pyrrolo-[1,2-a]-pyrimidine-4-one.

35 gm of 2-hydroxy-7,8-dihydro-6H-pyrrolo-[1,2-a]-pyrimidine-4-one were mixed with 400 cc of anhydrous acetonitrile, 32 gm of potassium carbonate and 50 gm of ethyl N-methyl-thiophosphoramido chloridate. The reaction mixture was agitated for 16 hours at room temperature and then the insolubles were eliminated by vacuum filtration. The filtrate was evaporated under reduced pressure and 55 gm of a red oil was obtained. This oil was purified by subjecting it to chromatography through a column of silica eluting with an acetone-chloroform-cyclohexane mixture (1:1:1). The fraction of Rf 0.3 was separated. The solvents were eliminated under reduced pressure and 9 gm of 2-(N-methyl-O-ethyl-thiophosphoramido-oxy)-7,8-dihydro-6H-pyrrolo-[1,2-a]-pyrimidine-4-one were obtained, which crystallized slowly giving yellowish crystals melting at 85°C.

Analysis:

$C_{10}H_{16}N_2O_3PS$; molecular weight = 289.295

Calculated:

41.52% C 5.57% H 14.53% N 10.71% P

Found:

41.1 5.5 14.1 10.5

EXAMPLE 3

2-(O-ethyl-N,N-dimethyl-thiophosphoramido-oxy)-7,8-dihydro-6H-pyrrolo-[1,2-a]-pyrimidine-4-one

22 gm of sodium methylate were introduced therein. The mixture was maintained under agitation until the temperature returned to 20°C. The precipitate formed was eliminated by filtration. The filtrate was evaporated to dryness. The residue was taken up in ether, triturated, and 88 gm of the sodium salt of 2-hydroxy-7,8-dihydro-6H-pyrrolo-[1,2-a]-pyrimidine-4-one was isolated by vacuum filtering.

Step B: 2-(O-ethyl-N,N-dimethyl-thiophosphoramido-oxy)-7,8-dihydro-6H-pyrrolo-[1,2-a]-pyrimidine-4-one

88 gm of a sodium salt of 2-hydroxy-7,8-dihydro-6H-pyrrolo-[1,2-a]-pyrimidine-4-one and 63 cc of ethyl N-dimethyl-thiophosphoramido-chloridate were introduced into 700 cc of acetonitrile. The mixture was heated to reflux for 33 hours. The precipitate formed was eliminated by filtration. The filtrate evaporated to dryness and 100 gm of red oil was obtained. This oil was subjected to chromatography through silica eluting with a cyclohexane-acetone-chloroform mixture (1:1:1) in order to obtain some yellowish crystals which were purified by washing with essence G. 27.5 gm of 2-(O-ethyl-N,N-dimethyl-thiophosphoramido-oxy)-7,8-dihydro-6H-pyrrolo-[1,2-a]-pyrimidine-4-one were thus obtained melting at 63°C.

Analysis:

$C_{11}H_{18}N_2O_3PS$; molecular weight = 303.322

Calculated:

EXAMPLE 4

2,3-dihydro-7-(diethoxy-thiophosphoryloxy)-thiazolo-[3,2-a]pyrimidine-5-one

34 gm of 2,3-dihydro-7-hydroxy-thiazolo-[3,2-a]-pyrimidine-5-one and 28 gm of potassium carbonate were introduced into a solution of 35 cc of 0,0-diethyl chlorothiophosphate in 300 cc of acetonitrile. The solution thus obtained was heated to reflux for 16 hours. The precipitate formed was eliminated by filtration. The filtrate was evaporated to dryness. A red oil was obtained which was subject to chromatography through silica eluting with a cyclohexane-ethyl acetate mixture (2:8). 19 gm of 2,3-dihydro-7-(diethoxy-thiophosphoryloxy)-thiazolo-[3,2-a]-pyrimidine-5-one was obtained having a refractive index $n_D^{30} = 1.5711$.

Analysis:

$C_{10}H_{15}N_2O_4PS_2$; molecular weight = 322.344

Calculated:

EXAMPLE 5

2-Diethoxythiophosphoryloxy-3-bromo-7,8-dihydro-6H-pyrrolo-[1,2-a]-pyrimidine-4-one

1.1 gm of 2-hydroxy-3-bromo-7,8-dihydro-6H-pyrrolo-[1,2-a]-pyrimidine-4-one were introduced into a suspension containing 0.8 cc of 0,0-diethyl chlorothiophosphate and 0.7 gm of potassium carbonate in 10 cc of acetonitrile. The suspension obtained was agitated for 48 hours. The insolubles were eliminated by

filtration. The filtrate was evaporated to dryness and a gray oil was obtained which was subject to chromatography through silica eluting of 2-diethoxythiophosphoryloxy-3-bromo-7,8-dihydro-6H-pyrrolo-[1,2-a]-pyrimidine-4-one were obtained melting at 111°C.

Analysis:

$C_{11}H_{16}BrN_2O_4PS$; molecular weight = 383.209

Calculated:

EXAMPLE 6

2-Diethoxythiophosphoryloxy-3-methyl-7,8-dihydro-6H-pyrrolo-[1,2-a]-pyrimidine-4-one.

Step A: The sodium salt of 2-hydroxy-3-methyl-7,8-dihydro-6H-pyrrolo-[1,2-a]-pyrimidine-4-one.

44.5 gm of 2-hydroxy-3-methyl-7,8-dihydro-6H-pyrrolo-[1,2-a]-pyrimidine-4-one and 14.5 gm of sodium methylate were introduced at 40°C into 400 cc of methanol. The solution obtained was agitated for 15 minutes at room temperature and then evaporated to dryness. The crystals obtained were triturated in ether and isolated by vacuum filtration. 134 gm of the raw sodium salt of 2-hydroxy-3-methyl-7,8-dihydro-6H-pyrrolo-[1,2-a]-pyrimidine-4-one were thus obtained.

Step B: 2-Diethoxythiophosphoryloxy-3-methyl-7,8-dihydro-6H-pyrrolo-[1,2-a]-pyrimidine-4-one.

134 gm of the raw salt obtained in Step A were introduced into a solution containing 42.5 cc of 0,0-diethyl chloro-thiophosphate in 500 cc of acetonitrile. The mixture was heated to reflux for 36 hours. The precipitate formed was eliminated by vacuum filtration and the filtrate was evaporated to dryness. A red oil was obtained which was subject to chromatography through silica eluting with a cyclohexane-acetone-chloroform mixture (1:1:1). A yellow oil of R_f 0.35 was obtained which was subject to chromatography again through silica eluting with a cyclohexane-ethyl acetate mixture (3:7). 20 gm of 2-diethoxythiophosphoryloxy-3-methyl-7,8-dihydro-6H-pyrrolo-[1,2-a]-pyrimidine-4-one were thus obtained having a refractive index $n_D^{30} = 1.5335$.

Analysis:

$C_{12}H_{19}N_2O_4PS$; molecular weight = 318.334

Calculated:

EXAMPLE 7

2,3-Dihydro-8-diethoxythiophosphoryloxy-4H-pyrimido-[2,1-b]-[1,3]-thiazine-6-one
(prepared according to the method of Schobert et al
Ann. Chem. 742,91, 1970)

21 gm of potassium carbonate and 28.5 gm of 0,0-diethyl chloro-thio-phosphate were introduced into 250 cc of acetonitrile. The mixture was heated to reflux for 3 hours and then the precipitate formed was eliminated by filtration. The filtrate was evaporated to dryness, then crystallized by the addition of ether. Some yellow crystals were obtained which were subject to chromatography through silica with elution with a cyclohexane-chloroform-acetone mixture (1:1:1). 20.1 gm of 2,3-dihydro-8-diethoxy-thio-

phosphoryloxy-4H-pyrimido-[2,1-b]-[1,3]-thiazine-6-one were thus obtained melting at 80°C.

Analysis:

$C_{11}H_{17}N_2O_4PS_2$; molecular weight = 336.37

Calculated:

39.29% C 5.09% H 8.33% N 9.20% P

Found:

39.5 5.1 8.2 9.2

EXAMPLE 8

1,6-Dihydro-4-dimethoxythiophosphoryloxy-azepino-[1,2-a]-pyrimidine-6-one

35 gm of 1,6-dihydro-4-hydroxy-azepino-[1,2-a]-pyrimidine-6-one and 27 gm of potassium carbonate were introduced into 350 cc of acetonitrile. 32 gm of O,O-dimethyl chloro-thiophosphate were then added, and the reaction mixture was agitated for 20 hours at room temperature. The mineral salts were eliminated by filtration. The filtrate was concentrated to dryness by distillation under reduced pressure. The residue was dissolved in a mixture of cyclohexane and ethyl acetate (1:1). The solution obtained was passed through florasil (activated magnesium silicate) and 27 gm of 1,6-dihydro-4-dimethoxy-thiophosphoryloxy-azepino-[1,2-a]-pyrimidine-6-one were obtained having a melting point of 99°C.

Analysis:

$C_{11}H_{17}N_2O_4PS$; molecular weight = 304.31

Calculated:

43.42% C 5.63% H 9.20% N 10.18% P

Found:

EXAMPLE 10

1,6-Dihydro-4-diethoxythiophosphoryloxy-5-isopropyl-azepino-[1,2-a]-pyrimidine-6-one

40 gm of 1,6-dihydro-4-hydroxy-5-isopropyl-azepino-[1,2-a]-pyrimidine-6-one, 25 gm of potassium carbonate and 29 cc of O,O-diethyl chloro-thiophosphate were introduced into 400 cc of acetonitrile. The reaction mixture was heated to reflux and maintained there for 6 hours. Thereafter the mixture was agitated for 60 hours at room temperature. The

mineral salts were eliminated by filtration. The filtrate was concentrated to dryness by distillation under reduced pressure. The residue was purified by chromatography through silica gel eluting with a mixture of cyclohexane and ethyl acetate (7:3). 50 gm of 1,6-dihydro-4-diethoxythiophosphoryloxy-5-isopropyl-azepino-[1,2-a]-pyrimidine-6-one were obtained having a melting point of 71°C.

Analysis:

EXAMPLE 11

2-Dimethoxythiophosphoryloxy-7,8-dihydro-6H-pyrrolo-[1,2-a]-pyrimidine-4-one

41 gm of 2-hydroxy-7,8-dihydro-6H-pyrrole-[1,2-a]-pyrimidine-4-one, 400 mg of topanol, 36.5 gm of potassium carbonate were introduced into a mixture of 300 cc of acetone and 30 cc of methanol. 40 gm of 0,0-dimethyl chloro-thiophosphate were added thereto. The reaction mixture was heated to reflux and maintained there for a period of an hour and 45 minutes. Thereafter, the reaction mixture was concentrated to dryness by distillation under reduced pressure. Water was added to the residue and the mixture was extracted with ethyl acetate. The organic phase was dried and concentrated to dryness by distillation under reduced pressure. The residue was crystallized from ethyl ether and 23 gm of 2-dimethoxythiophosphoryloxy-7,8-dihydro-6H-pyrrolo-[1,2-a]-pyrimidine-4-one were obtained having a melting point of 53°C.

Analysis:

$C_9H_{13}N_2O_4PS$; molecular weight = 276.25

Calculated:

EXAMPLE 12

2,3-Dihydro-7-dimethoxythiophosphoryloxythiazolo-[3,2-a]-pyrimidine-5-one

12 gm of 2,3-dihydro-7-hydroxy-thiazolo-[3,2-a]-pyrimidine-5-one and 9.8 gm of potassium carbonate were introduced into 200 cc of acetonitrile. 8.5 cc of O,O-dimethyl chloro-thiophosphate were introduced therein. The mixture was agitated for 64 hours at room temperature. The mineral salts were eliminated by filtration. The filtrate was concentrated to dryness by distillation under reduced pressure. The residue was subject to chromatography through silica gel with elution by a mixture of cyclohexane and ethyl acetate (2:8). 8 gm of 2,3-dihydro-7-dimethoxythiophosphoryloxythiazolo-[3,2-a]-5-pyrimidine-5-one were obtained having a melting point of 84°C.

Analysis:

$C_8H_{11}N_2O_4PS_2$; molecular weight = 294.29

EXAMPLE 13

1,6-Dihydro-4-diethoxyphosphoryloxy-azepino-[1,2-a]-pyrimidine-6-one

35 gm of 1,6-dihydro-4-hydroxy-azepino-[1,2-a]-pyrimidine-6-one were introduced into 250 cc of triethyl phosphite. The reaction mixture was heated to 75°C and maintained there for 16 hours. A slight insolubility was eliminated by filtration. The filtrate was concentrated to dryness by distillation under reduced pressure. The residue was subject to chromatography through silica gel eluting with a mixture of acetone, chloroform and cyclohexane (1:1:1), then subject to chromatography through florasil (activated magnesium silicate) eluting with a mixture of acetone and chloroform (1:1) and concentrated to dryness under reduced pressure. 21 gm of 1,6-dihydro-4-diethoxyphosphoryloxy-azepino-[1,2-a]-pyrimidine-6-one were obtained containing about 10% of triethyl phosphite having a refractive index n_D^{24} = 1.4994.

EXAMPLE 14

2-Diethoxythiophosphoryloxy-6,7,8,9-tetrahydropyrido-[1,2-a]-pyrimidine-4-one

8.31 gm of 2-hydroxy-6,7,8,9-tetrahydropyrido-[1,2-a]-pyrimidine-4-one and 6.91 gm of potassium carbonate were introduced into 100 cc of acetonitrile. 7.9 cc of 0,0-diethyl chloro-thiophosphate were added thereto. The mixture was agitated for 48 hours at room temperature. The insolubles formed were eliminated by filtration. The filtrate was concentrated to dryness. The residue was subject to chromatography through silica gel with elution by a mixture of cyclohexane and ethyl acetate (4:6). 7.96 gm of 2-diethoxythiophosphoryloxy-6,7,8,9-tetrahydro-pyrido-[1,2-a]-pyrimidine-4-one were obtained having a refractive index of n_D^{25} = 1.5410.

Analysis:

$C_{12}H_{19}N_2O_4PS$; molecular weight = 318.33

Calculated:

EXAMPLE 15

2-Dimethoxythiophosphoryloxy-6,7,8,9-tetrahydropyrido-[1,2-a]-pyrimidine-4-one

17 gm of 2-hydroxy-6,7,8,9-tetrahydropyrido-[1,2-a]-pyrimidine-4-one and 24 gm of potassium carbonate were introduced into 200 cc of acetonitrile. 12 cc of 0,0-dimethyl chloro-thiophosphate were added thereto. The mixture was agitated for 16 hours at room temperature and next the reaction mixture was heated to 60°C and maintained at this temperature for one hour and thirty minutes. The mineral salts were eliminated by filtration. The filtrate was concentrated to dryness. The residue was subject to chromatography through silica gel with elution by a mixture of cyclohexane and ethyl acetate (2:8). 9 gm of 2-dimethoxythiophosphoryloxy-6,7,8,9-tetrahydropyrido-[1,2-a]-pyrimidine-4-one were obtained having a melting point of 111°C.

Analysis:

$C_{10}H_{15}N_2O_4PS$; molecular weight = 290.28

Calculated:

41.38% C 5.21% H 9.64% N 10.66% P

EXAMPLE 23

Study of the insecticidal properties of 2-diethoxythio designated hereafter as Compound A.

A. Test on *Aphis fabae*

Some bean plants were utilized which were divided into three groups:

a. The first group of plants was treated by Compound A, 1 ml of solution containing 5 mg of Compound A per liter was sprinkled on each leaf. Each leaf was infested with 20 plant lice and each leaf was encircled with gauze in order to hinder the departure of the plant lice.

b. The second group of plants was treated in the same fashion as the group of plants of group a), but replacing Compound A by Dimethoate (or dimethyl S-(N-methylcarbamoylmethyl)-phosphorothiolothionate).

c. The third group of plants, or the control group, was not treated. Each leaf was directly infested with 20 plant lice. The living insects and those killed by the two insecticides were counted. The activity of Compound A and that of Dimethoate was expressed as a percentage of the reduction of the number of living insects. The results are given in the following Table I:

TABLE I

Product	Concen- tration in mg/l	Activity		
		2 hours	24 hours	48 hours
Compound A	5	0	100	100
Dimethoate	5	3.6	100	100

Conclusion: Compound A possesses a very good activity on *Aphis fabae*.

B. Test on *Ceratitis capitata*

In this test covered Petri dishes are utilized which are divided into three groups:

a. In the dishes of group a), 1 ml of acetonitrile solution of Compound A was inserted at concentrations of 100, 10, 7.5, 5, 2.5 and 1 mg of Compound A per liter.

b. In the dishes of group b), the corresponding solutions of Dimethoate were utilized in place of those of Compound A.

c. In the dishes of group c), no solution was inserted and it was used as the control group.

Twenty *Ceratitis capitata* flies aged three days were placed in each Petri dish of group a), b) and c), and the lids were placed thereon. The living insects and those killed by Compound A and Dimethoate at different intervals of time were counted. The activity of compound A and that of Dimethoate are expressed as a percentage of the reduction of the number of living insects.

The results are given in Table II below:

TABLE II

Product	Concentration in mg/l	Activity	
		1 hour	24 hours
Compound A	100	100	100
	10	72.2	95.8
	7.5	76.5	85.1
	5	37.5	56.3
	2.5	20.0	30.0
	1	2.2	2.2
Dimethoate	10	57.6	100
	5	41.2	98.0
	2.5	5	64.0
	1	5.2	2.0

Conclusion: Compound A has a very good activity on *Ceratitis capitata*.

C. Test on *Prodenia litura* (caterpillars)

Salad leaves which were broken into bits of 8 mm in diameter were utilized. Each piece of leaf was placed in a box at a ratio of one piece of leaf per box, and the boxes were divided into three groups:

a. The pieces of salad leaves of the boxes in group a) 5 were treated with the Compound A at an amount of 4 μ l of aqueous solution of Compound A on each piece, and with solutions containing 5,000, 2,500, 1,250 and 625 mg of Compound A per liter.

b. Operating in the same manner for group b), but 10 Compound A was replaced by Carbaryl (or 1-N-naphthyl-N-methylcarbamide).

c. Nothing was placed on the bits of leaf in group c).

In each box of groups a), b) and c), a caterpillar was 15 inserted. The caterpillars remaining alive and those killed by the two insecticides at different intervals of time were counted. The activity of Compound A and that of Carbaryl are expressed as a percentage of the reduction of the number of living caterpillars. The results are given in Table III below.

20

TABLE III

Product	Concentration in mg/l	Amount of active product absorbed in μ g	Activity		
			1 hour	24 hours	48 hours
Compound A	5000	20	100	100	100
	2500	10	100	100	100
	1250	5	90	100	100
Carbaryl	625	2.5	80	100	100
	5000	20	100	100	100
	2500	10	100	100	100
Carbaryl	1250	5	100	100	100
	625	2.5	83.3	46.6	66.0

Conclusion: Compound A possesses a very good activity on *Prodenia litura*, superior to that of carbaryl.

EXAMPLE 24

Study of the insecticidal activity of
2-dimethoxythio-phosphoryloxy-7,8-dihydro-6H-pyrrolo-[1,2-a]-pyrimidine-4-one

A. Test on *Blatella germanica*:

This test was effected by micro-contact. Larvae of the cockroaches chosen according to their length received a micro-drop of an aceton solution of the product to be tested between the second and third pair of legs. After the treatment, the "test insects" were held in semi-darkness at 20°C, and were nourished. The controls were made 24 hours, 48 hours, and then 5 days after treatment. The experimental results expressed as a percentage of mortality are given in Table IV below:

TABLE IV

	5,000 p.p.m.	1,250 p.p.m.	625 p.p.m.
24 hours	100	90	25
48 hours	100	95	35
5 days	100	100	90

60

B. Test on *Musca domestica*

This test was effected by micro-contact. The flies received a micro-drop of aceton solution of the product being tested on the dorsal thorax, after having been put to sleep with ether. The insects were maintained at 20°C and 50% relative humidity. They were fed with milk or water. The controls were effected one hour,

and then 24 hours after the treatment. The experimental results expressed as a percentage of mortality are given in Table V below:

TABLE V

	5,000 p.p.m.	2,500 p.p.m.	500 p.p.m.
1 hour	96	96	30
24 hours	100	98	74

C. Test on *Aphis fabae*

This test was effected by contact-ingestion on beans. After pulverization of the solution of the product tested, the infestation rate of 20 individual aphids per plant of beans was made. The bean plants were wrapped in gauze in order to hinder the departure of the plant lice. A counting of living and dead insects as a function of time was made. The results are expressed in a percentage of Abbott efficacy (taking into account the controlled test).

The results obtained are given in Table VI below:

TABLE VI

	100 p.p.m.	10 p.p.m.
1 hour	60	0
24 hours	100	39
48 hours	100	100

45

D. Test on *Prodenia litura*

This test was effected on the caterpillars of *Prodenia litura*. It is a test by ingestion. An aceton solution of the product to be tested was deposited on bits of salad leaves of 8 mm in diameter which were disposed in closed plastic boxes of 5 cm in diameter. Fifteen caterpillars were utilized per treatment (caterpillars aged 10 days in average). The caterpillars were held at 20°C and 50% relative humidity, and were fed. The controls were effected 1 hour, 24 hours and 48 hours after treatment. The experimental results obtained expressed as a percentage of mortality are given in Table VII below:

TABLE VII

	500 p.p.m.	250 p.p.m.	125 p.p.m.	62.5 p.p.m.
1 hour	0	0	0	0
24 hours	100	80	70	80
48 hours	100	90	100	100

65

E. Test on larvae of domestic flies (*Musca domestica*)

This test was effected by contact-ingestion. It consists of depositing 2 ml of an acetonic solution of the compound to be tested on 1 gm of bran, placed in a watch glass. The solvent was allowed to evaporate. Then the treated bran was deposited in a plastic box. Two ml of milk was added and after having been mixed the material was contaminated with 20 larvae of domestic flies aged 3 to 4 days. There were 3 tests by concentration. The larvae were maintained at 20°C and 50% relative humidity. The controls were effected 48 hours and 8 days after the treatment. The experimental results obtained expressed as a percentage of mortality are given in Table VIII below:

TABLE VIII

	5,000 p.p.m.	500 p.p.m.	15
48 hours	37	28	
8 days	97	87	20

Conclusion:

In the different test followed, the product tested is endowed with a very interesting insecticidal activity.

The preceding specific embodiments are illustrative of the practice of the invention. It is to be understood, however, that other expedients known to those skilled in the art may be employed without departing from the spirit of the invention.

We claim:

1. An organophosphate ester having the formula

wherein

n represents an integer from 2 to 3,

Y' represents a member selected from the group consisting of hydrogen, alkyl having one to six carbon atoms, halo and alkylthio having one to six carbon atoms,

X represents a member selected from the group consisting of sulfur and oxygen,

R'' represents an alkyl having one to four carbon atoms,

R'' represents a member selected from the group consisting of alkoxy having one to four carbon atoms, alkoxyalkoxy having one to four carbon atoms alkoxyalkoxy having one to four carbon atoms in each alkyl, and

where R' and R'' are members selected from the group consisting of hydrogen and alkyl having one to three carbon atoms.

2. An organophosphate ester of claim 1 wherein Y' is hydrogen.

3. An organophosphate ester of claim 1 being 2,3-dihydro-8-diethoxythiophosphoryloxy-4H-pyrimido-[2,1-b]-[1,3]-thiazine-6-one.

4. An organophosphate ester of claim 1 being 2,3-dihydro-7-dimethoxythiophosphoryloxy-thiazolo-[3,2-a]-pyrimidine-5-one.

* * * * *

UNITED STATES PATENT OFFICE
CERTIFICATE OF CORRECTION

Patent No. 3,857,838 Dated December 31, 1974

Inventor(s) Jacques Perronnet et al. Page 1 of 2

It is certified that error appears in the above-identified patent and that said Letters Patent are hereby corrected as shown below:

Column 5, line 4, "-" omitted in [1,2'-'a]

Column 5, line 4 and 5, "pyrrodo-4-pyrimidone" should have been omitted.

Column 6, lines 41 and 42, "4-hydroxy-azepino-[1,2-a]-pyrimidine-6-one 5-bromo-1,6-dihydro" should read -- 4-hydroxy-5-bromo-1,6-dihydro azepino-[1,2-a]-pyrimidine-6-one --.

Column 8, line 5-8, insert -- Step A: The sodium salt of 2-hydroxy-7,8-dihydro-6H-pyrrolo-[1,2-a]-pyrimidine-4-one. 60 gm of 2-hydroxy-7,8-dihydro-6H-pyrrolo-[1,2-a]-pyrimidine-4-one were introduced into 400 cc on methanol. Next --.

Column 9, line 3, insert -- with an ethyl acetate-cyclohexane mixture (9:1). 406 mg -- after the word "eluting"

Column 9, line 56, before "pyrimido" insert -- 24.6 gm of 2,3-dihydro-8-hydroxy-4H- --.

Column 13, line 68, "(1:1:11)" should be -- (1:1:1) --.

Column 14, line 60, "0/0" should be -- % --.

Column 14, line 66, before "7,8-dihydro" insert -- 2-(Di-n-butyloxy-thiophosphoryl)- --.

Column 15, lines 19 - 38, all material after "50.3 6.9 7.6 8.8" should be cancelled as duplicate of lines 1-19.

Column 15, line 58, "c" in formula should be -- C --.

UNITED STATES PATENT OFFICE
CERTIFICATE OF CORRECTION

Patent No. 3,857,838 Dated December 31, 1974

Inventor(s) Jacques Perronet et al. Page 2 of 2

It is certified that error appears in the above-identified patent and that said Letters Patent are hereby corrected as shown below:

Column 17, line 7, the "4" in after ,ul should be omitted.

Column 19, line 24, "test:" should be -- tests --.
